CLAIM

I claim the ornamental design for a hole puncher, as shown and described.

DESCRIPTION

FIG. 1 is a perspective view of a hole puncher showing my new design;

FIG. 2 is a side elevational view of the hole puncher as shown in FIG. 1;

FIG. 3 is a front elevational view of the hole puncher as shown in FIG. 1;

FIG. 4 is a rear elevational view of the hole puncher as shown in FIG. 1;

FIG. 5 is a top view of the hole puncher as shown in FIG. 1; and,

FIG. 6 is a bottom view of the hole puncher, as shown in FIG. 1.

The broken line showing of a star-shaped removable die portion in FIG. 6 is for illustrative purposes only and forms no part of the claimed design.
